DISPLAY CONTAINER

Albert H. Newman, Chicago, Ill.

Application June 20, 1936, Serial No. 86,250

2 Claims. (CL 206—44)

My invention relates to novel and improved display containers having transparent walls so constructed as to permit of their use in forming panels and walls of any form or shape, thus providing means for the creation of containers having distinctiveness, originality, beauty, and sales appeal.

Because of difficulties heretofore considered insurmountable, containers of this character have been made in but few forms, with imperfect locking means, susceptible to bulging, fracturing, and rupturing under slight tensile action. The vertical walls of containers of this character are constructed of flexible, transparent material, such for example, as regenerated cellulose, generally sold under such trade names as Cellophane, Protectoid, Kodapac, and the well-known Celluloid. Because of the intrinsic nature of this material, it is impractical, both economically and mechanically, to construct containers, or similar receptacles, by a mere substitution of the transparent sheet-like material for the prior materials. Cellulose and its derivatives, under normal conditions of temperature, have little affinity for adhesive substances, and mechanical bonds formed solely through the medium of such agents are not lockfast, and walls so formed may collapse, fracture, rupture or rend under slight compression or tensile action. Anchoring the vertical walls by means of staples or like mechanical appliances is vulnerable to the same objections in even a greater degree, as such fastening means may come directly in contact with the merchandise displayed in the container, marking, scratching and abrading the same.

The edges of the vertical walls of containers so formed present the surface of least resistance, and extremely slight pressure applied thereto will cause the walls to bend or bulge, thus diminishing their utility, and aesthetic appeal. To assist in the generation of sales appeal, induce consumer acceptance, and overcome sales resistance by a direct appeal to the eye, is the functional objective of containers of this character. I have achieved this objective and have invented means, not only for the provision of a strong, durable, rigid container having vertical walls of flexible transparent material, but a container that may be constructed in a variety of forms and shapes to blend and harmonize with the peculiarities of the merchandise displayed therein, thus enhancing the sales appeal of the product, which can, if desired, be also wrapped in transparent material.

I have also invented means for reinforcing the

edges of the transparent material in a positive manner of inexpensive material, conveniently folded, and adapted to mass production. Owing to the structure of material like regenerated cellulose a rend originating in the edge thereof encounters no resistance, and may be said to advance with the facility of water flowing over a smooth and even surface. By the invention of my improved locking means I have eliminated this highly objectionable feature in a simple and inexpensive manner.

I have also invented means for the production of a transparent display container with a demountable floor adapted to sustain light or heavy loads. I have also invented inexpensive and conveniently operative anchoring means for securing the bottom or floor of the container.

My invention in addition to the foregoing features permits the utilization of sheets of transparent sheet-like material having a lighter gauge, thus effecting substantial economy in the cost of production, and at the same time providing a container of greater strength and durability than others heretofore produced. In the practice of my invention it is not necessary to cut flaps having openings of various dimensions and material and labor is thus conserved.

This invention also consists in certain other features of construction and in the combination and arrangement of the several parts to be hereinafter fully described, illustrated in the accompanying drawings and particularly pointed out and defined in the claims hereto appended.

In describing the invention in detail, reference will be had to the accompanying drawings wherein like characters of reference denote like or corresponding parts throughout the several views, and in which:

Figure 1 is a perspective view of the metal edging with which the edges of the walls are reinforced, and from which the ledge is formed to sustain the floor of the container.

Figure 2 a perspective view of the blank from which the transparent walls are formed;

Figure 3 a perspective view of an anchoring tab employed in one embodiment of my invention;

Figure 4 a perspective view of the metallic edging after the initial fold has been executed, but before transparent material has been inserted in the channel.

Figure 5 a perspective view of the edging disclosing the cellulose walls in contact therewith.

Figure 6 a perspective view of the edging and transparent material after the second fold has been performed.

Figure 7 is a perspective view of a rectangular open-top container constructed in accordance with the invention.

Figure 8 is a vertical cross section taken on the 5 lines 8, 8, of Figure 7.

Figures 9, 10, and 11, are perspective views showing a few of the different forms in which my invention may be embodied.

As heretofore distinctly pointed out, and illustrated in the drawings, my invention may be employed in the production of containers of various configurations and forms. The embodiment I have chosen to illustrate and describe in detail is a box of conventional rectangular shape with 15 an open top and transparent walls. The reference numeral 10, indicates the side or lateral walls, and the numerals 11 and 12 indicate the front and rear walls respectively. The walls are constructed from an integral blank of flexible 20 transparent material cut to the desired size and shape to form blank 13. The upper and lower edges of the blank 13 are reinforced by metallic edging 14. The edging is formed from a blank 25 of light sheet metal of sufficient strength and flexibility to be adapted to this purpose. The oblong metallic strip 14 is folded longitudinally upon itself along the plane indicated by dotted lines 7 in Figure 1, so as to provide a longitudinal channel or groove adapted to the reception 30 of the rectangular blank 13. The channel is designated by the numeral 15. The blank 13 is disposed in the channel 15, parallel to the axis of the fold. The lateral walls of the edging are then compressed transversely. This anchorage 35 does not provide a lockfast attachment. Joints so formed will permit the cellulose to slide and work loose under slight tensile action. The smooth and even surface of the cellulose presented to the sheet metal causes the external 40 friction to be exceedingly slight, and under tensile action, bulging, fracturing, or rupturing of the walls and deformation of the container may result. To obviate these objectionable features, and at the same time provide a ledge adapted to 45 support a horizontal wall 16, the seam 17 is folded inwardly along its longitudinal axis so as to form ledge 18, which provides a lockfast attachment for the transparent walls, and at the same time a ledge adapted to support a horizontal wall of any material. Anchorage tabs 19

may be placed in the channel 15 to fixedly secure the horizontal wall 16 against vertical displacement. The tongue 20 of the tab 19 may be anchored in the channel 15 by compression or folding so that the body of the tab 19, indicated 5 by the numeral 21 may be arcuately elevated or depressed to remove or secure the horizontal floor against vertical displacement.

From Figure 9 it will be observed that the side walls 24 may be conveniently folded so as to form 10 in association with the circular base 25 a cylinder-like structure, and from Figure 10 it will be observed that the corners of the container may be arcuated as indicated by reference numerals 15 26 in both Figures 10 and 11.

While I have confined my detailed description to the construction of the edging and lock-forming elements constituting the base of the container, it is obvious that the upper edge 9 is formed in the same identical manner as the 20 lower edge. It is equally obvious that changes and modifications can be made in the exact details shown, and therefore, I do not wish to be limited in any particular, rather what I desire to secure and protect by Letters Patent of the 25 United States is:

1. A container adapted for the display of goods contained therein and the dispensing of the same therefrom comprising a generally prismatic structure formed with a single parallel edge sheet 30 of transparent flexible material forming its vertical walls, rigid metallic edge members secured to the upper and lower edges of said structure, a removable floor member positioned upon said lower edge member and horizontal anchoring 35 tabs fixedly secured in said lower edge member for supporting said floor.

2. A container of the class described comprising an open-ended box-like structure having vertical walls formed of a single sheet of parallel 40 edged flexible transparent material, metallic strips secured to said upper and lower parallel edges, said lower metallic strip secured to the lower edge of said material by a double fold of the material and metal strip, said metal strip 45 forming an inwardly extending edge, a removable bottom wall supported thereon and horizontally disposed anchoring tabs secured in said metal strip overlying said bottom wall.

ALBERT H. NEWMAN. 50
